UNITED STATES PATENT OFFICE

2,502,492

ELECTRON VELOCITY MODULATION DEVICE

Stanley Gordon Tomlin, Aldwych, London, England, assignor, by mesne assignments, to International Standard Electric Corporation, New York, N. Y., a corporation of Delaware

Application March 26, 1945, Serial No. 584,903
In Great Britain March 28, 1944

7 Claims. (Cl. 315—5)

1

The present invention relates to electron discharge devices of the electron velocity modulation type having means for focussing the electron beam.

In cases of particular interest, magnetic focusing means are used, and in order to secure the best performance of such devices it is necessary to exercise some care in aligning the focussing magnetic field with the electron beam so that the maximum number of electrons emitted from the cathode may be effectively utilised.

It is necessary also to provide for conveniently replacing such devices in apparatus where they are used, and it is very troublesome, if not impracticable, to have to carry out an aligning operation every time one of the devices is changed or replaced, since such an operation requires skill, and test means.

The object of the present invention, therefore, is to provide means whereby such devices may be replaced in the apparatus in such manner as to be automatically correctly placed with respect to the focussing field.

The electron velocity modulation devices with which this invention is concerned will be called for convenience velocity modulation devices, and are of the well known kind in which an electron beam is directed through pairs of electrodes connected to a resonating system or systems and constituting a gap in which the electron velocities are modulated and also a gap in which energy may be extracted from the beam, with a drift space between the gaps. Such a device may be an amplifier, modulator, or generator, according to the circumstances of its operation.

The invention will be illustrated by a specific embodiment shown on the accompanying drawings in which:

Fig. 1 shows diagrammatically part of velocity modulation device having a disc sealed through the envelope;

Figs. 2 and 3 show side and end views respectively, of an electrical wave apparatus including a velocity modulation device of the kind shown in Fig. 1;

Fig. 4 shows locating holes in the disc of the device;

Fig. 5 shows a device placed in a jig for punching the locating holes;

Fig. 6 shows a side view of a velocity modulation device similar to those shown in the previous figures, but assembled in a protective metal case; and

Fig. 7 shows a sectional view of the device and case taken at the line 7—7 of Fig. 6.

2

The invention will be described in relation to a particular type of velocity modulation device, though the same principles are also applicable to other types, the details being modified to suit the particular features of the device concerned. The device in the present case is assumed to be one in which a co-axial line resonator is excited by an electron beam projected across it, such as is described in U. S. Patent No. 2,320,860. In the present case, as indicated diagrammatically in Fig. 1, the tubular resonator 1 is enclosed in a glass envelope 2 through the walls of which is sealed an annular metal disc 3 integral with the resonator inside, and forming a terminating flange for the resonator. The envelope is shown broken away at the left-hand side and is supposed to continue to a suitable base with terminals not shown, and to contain a press also not shown from which the cathode 4 and target 5 are supported. Electrons are fired across the resonator 1 from the cathode 4 to the target 5 for the purpose of exciting the resonator. It will be understood that Fig. 1 is not intended to illustrate the device in any detail since it is of a well known type, but the figure is principally used to show the relation between the resonator and the disc.

The focussing magnetic field is directed parallel to the electron beam by a magnet not shown external to the device.

Figs. 2 and 3 show one way in which the velocity modulation device may be coupled to a co-axial transmission line, for example, which may form part of an apparatus or system. The outline of part of the envelope 2 of the device is shown, and the end of the envelope extends into a metal tube 6 having a flange 23 which may constitute the outer conductor of a co-axial transmission line. The disc 3 of the device is clamped between the flange 23 and a plate 8. The plate 8 has a U-shaped slot at 9 wide enough to accommodate the envelope of the device. Two locating pins 10 and 11 are fixed in the flange 23 and extend through corresponding holes 12 and 13 in the disc 3, shown in Fig. 4, and into other holes in the plate 8.

The central conductor 17 of the transmission line may be coupled to the central conductor of the co-axial line resonator 1 by means of a small condenser plate 18 sealed through the envelope 2, and explained in the specification of co-pending application 636,018. A focussing magnet 14 is adjustably fixed to the plate 8 by means of a clamping plate 15 and screws 16.

Fig. 5 shows one method of punching the lo-

cating holes 12 and 13. A jig or tool is used comprising a plate 8A exactly similar to the plate 8 having clearance holes corresponding to the pins 10 and 11, a die 19 carrying punches 20 and 21 registering with these clearance holes, and a magnet 14A, closely similar to the magnet 14, and symmetrically fixed to the plate 8A. A velocity modulation device of the kind described with reference to Fig. 1, complete except for the punching of the holes, is inserted in the jig with the disc 3 clamped loosely between the plate 8A and the die 19. A suitable socket not shown connected to a test circuit is fixed on the base 22 of the device. This test circuit should include the means for generating the electron beam under the specified conditions and for measuring the current flowing to the target 5. The device is then rotated about its axis with respect to the magnet until a maximum beam current is obtained. This indicates that the maximum number of electrons are fixed through the resonator. The plate 8A and die 19 are now firmly clamped and the punches 20 and 21 are driven through the disc thus making the desired holes.

In this way a marker line is defined by the two holes related to the direction of the electron beam in the same particular manner determined by the focussing test, in all the velocity modulation devices.

The next step in the process is to fix the magnet 14 in all specimens of the apparatus with which the velocity modulation device is to be used. It is found that the effective direction of the magnetic field is somewhat variable in different magnets manufactured to the same specification. Accordingly a standard sample of the velocity modulation device with the two holes punched in the disc is inserted in each apparatus in the manner explained with reference to Figs. 2 and 3, and the test circuit is connected to the base as before. The clamping screws 16 are loosened, and the magnet 14 is then adjusted until a maximum beam current is obtained. The clamping screws 16 are then tightened.

This having been done, any velocity modulation devices with the holes punched in the manner described can be inserted in the apparatus and will take up the proper position automatically without the necessity for any aligning tests, so long as the magnet 14 is not afterwards moved.

In order to allow for slight manufacturing differences in the distance between the two pins 10 and 11 in different samples of the apparatus, one of the holes, for example 13, Fig. 4, may be slightly elongated radially.

It will be seen that if the two holes are punched diametrically opposite to one another, there will be two possible positions for the device in the apparatus differing in orientation by 180°. It may be found that these two positions are not equally good in all devices, so in order to ensure that the best position is selected, one of the two holes and the corresponding locating pin may be made larger than the other, or a third hole and pin may be provided, or the two holes 12 and 13 may be punched so that they are angularly spaced by less than 180°, or so that they are at different distances from the centre. If a third hole and pin are used the three holes should, of course, be unsymmetrically arranged so that there is only one possible position in which all the pins and holes can register. The third hole could be rather larger than its pin, so that accurate registration in the case of this hole is rendered unnecessary.

If the arrangements for fixing the device in the apparatus are such that it will be properly centred axially by other means, while able to rotate, only one pin and hole might be necessary to align the device in the correct position.

Sometimes it is desirable to provide the velocity modulation device with a protective case, and then a slightly different method of locating the device is preferable. Referring to Figs. 6 and 7, the protective case comprises a metal tube 24 having a flange 25 at the upper end. The upper part of the tube is cut away on either side as indicated in Fig. 6 so as to form a pair of diametrically opposite tongues 26, of which only one can be seen in Fig. 6, connecting the lower part of the tube 24 to the flange 25, which thus assumes practically the form of an annular disc. Inside the lower end of the tube 24 is secured in any suitable way a base 22 of insulating material carrying the usual pin terminals for the velocity modulation device.

The envelope 2 of the device is inserted into the tube 24 and the lead-out wires 27 are threaded through the pin terminals and soldered thereto in the usual way. These wires should be left sufficiently long to allow the device to be rotated through a moderate angle inside the tube 24.

The disc 3 of the velocity modulation device rests upon the flange 25 and is clamped thereto by an annular disc or plate 28 having a central hole large enough to clear the upper part of the envelope 2. The disc 28 is of somewhat larger diameter than the flange 25 and is fixed thereto by screws 29.

Suitably placed locating holes 30 are already drilled in the disc 28. A test jig arranged similarly to Fig. 5 is provided, but with fixed locating pins instead of the punches 20 and 21 adapted to engage the locating holes 30. The screws 29 are loosened sufficiently to allow the velocity modulation device to be rotated inside the tube 24 until a maximum beam current is measured as before. The screws 29 are then tightened.

The apparatus Figs. 2 and 3 will be provided with locating pins corresponding to the holes 30, and the focussing magnet 14 may be adjusted in the manner already explained. It will be understood that the tube 24 is cut away at the upper end in the manner described in order to allow the poles of the magnet closely to approach the envelope 2 in the neighborhood of the electron beam.

The disc 28 need not be larger in diameter than the flange 25, and the locating holes 30 could be arranged anywhere therein, but they should not overlap the disc 3 of the velocity modulation device. If they should overlap the flange 25, then, if desired, corresponding locating or clearance holes may be drilled in this flange to allow the locating pins to pass through both the disc and the flange.

The locating holes 30 may be arranged, dimensioned, and spaced in any of the ways suggested for the locating holes such as 12 and 13 punched in the disc 3 of the velocity modulation device, in order to ensure that the device can only be placed in one position in the apparatus in which it is used.

When the adjustment of the device inside the protective case has been made, the screws 29 may be riveted over or sealed with solder or otherwise fixed to prevent the adjustment from being afterwards altered.

It is to be noted, however, that the velocity modulation devices according to the invention are not necessarily constructed in the forms which have been chosen to illustrate the invention.

tion. In particular, they may not have any such disc as 3 sealed through the envelope. In such cases, other locating means capable of defining a marker line related in a definite way to the direction of the electron beam must be devised.

Thus, referring to Fig. 5, a velocity modulation device having no disc might be fixed in position by means of an annular clamp grasping the circular base 22. This would allow the velocity modulation device to be rotated with respect to the magnet 14A into the proper position. A radial hole drilled into the base 22 would then provide a marker radius related to the direction of electron beam. A corresponding locating pin associated with the annular clamp provided in the apparatus corresponding to Figs. 2 and 3 would then fix the position of the device, the magnet 14 being, of course, adjustably fixed with reference to the clamp so that it can be rotated about the axis of the device. Clearly two or more radial holes with corresponding pins could be used to define a marker line with respect to the electron beam. Other like arrangements can clearly be devised according to the same principles for other type of device. It should be noted that a single locating hole can only be used if the position of the axis of the device is otherwise determined, so that the hole in this case also effectively defines a marker line which is the radius drawn from the axis to the hole.

What is claimed is:

1. An electrical apparatus for generating ultra high frequency oscillations comprising an envelope enclosing an electron discharge device of the velocity modulation type, said discharge device including a cavity resonator and means for generating an electron beam, means about said envelope for focussing said beam in a beam path through said resonator, and locating means between said focussing means and said discharge device for locating said device in a definite position with respect to said focussing means, said locating means including means connected to said discharge device for defining a particular marker line thereon whereby a maximum number of the beam electrons are always focussed to be effectively utilized.

2. Apparatus according to claim 1 in which said discharge device includes a metal disc sealed through said envelope in a position parallel to said beam path and said marker defining means includes locating holes in said disc in a definite position with respect to said beam path.

3. Apparatus according to claim 2 in which said locating means includes a protective case mounted about said envelope and provided with apertures for said focussing means, a plate connected to said case and provided with additional locating holes aligned with said locating holes in said disc, and adjustable clamping means clamping said plate and said disc and said focussing means.

4. An apparatus according to claim 3 in which said cavity resonator comprises a coaxial line type resonator, said disc being of annular shape and attached to said resonator at one end forming a terminating flange therefor.

5. An electrical apparatus for generating ultra high frequency oscillations comprising an envelope enclosing an electron discharge device of the velocity modulation type, said discharge device including a cavity resonator and a metal disc connected to said resonator and sealed through said envelope and means in said envelope for generating an electron beam, a magnetic focussing means mounted about said envelope for focussing said beam in a beam path through said resonator in a direction parallel to said disc, said disc being provided with locating holes therein in a definite position with respect to said beam path, and mounting means between said magnetic focussing means and said disc in said holes for locating said magnetic focussing means in a definite position with respect to said beam path whereby a maximum number of the beam electrons are always focussed to be effectively utilized.

20 6. Apparatus according to claim 5 in which said disc is provided with two diametrically opposite locating holes, one of said holes being larger than the other.

7. An electrical apparatus for operation with an electron beam comprising an electron discharge device including a cavity resonator, means for generating an electron beam and an envelope enclosing said beam generating means and at least a portion of said resonator, means about said envelope for directing said beam in a path through said resonator, and locating means between said directing means and said envelope for locating said focusing means in a definite position with respect to said beam generating means, said locating means including means connected to said discharge device for defining a particular marker line thereon whereby a maximum number of the beam electrons are always directed to be effectively utilized.
